CUTTING AND WINDING MACHINE

Oscar I. Judelson, Park Ridge, N. J.

Application May 26, 1936, Serial No. 81,847

23 Claims. (Cl. 164—65)

My present invention relates to machines for cutting and winding fabrics and it is especially useful for cutting knitted textile fabrics such as are made of silk, rayon and other materials. It is common practice to knit the textile fabrics in the form of a long tube and it is also common to slit the tubular fabric in order to form two strips each of a single thickness of flat fabric suitable for manufacture into garments and for other purposes. The present invention includes a machine having a device for cutting or slitting the flattened tubular fabric at opposite sides so that the tubular fabric is divided into two flat strips; and the machine also includes means for rolling up the two strips of fabric formed by the cutting of the tube.

In Letters Patent No. 1,640,833, I showed and described a machine for slitting tubular fabric. The present machine is so designed as to slit the flattened tubular fabric along both crease lines to form two strips of fabric, each composed of half of what was the tube before the slitting operation took place. The machine is also adapted to wind up the strips of fabric and it is adapted to wind the strips with the outside of the fabric turned outwardly on the wound roll, or to wind it up with the outer side of the fabric turned inwardly of the wound roll. The two strips of fabric cut from the same tube may therefore both be wound with the outer side of the fabric on the outside of the roll or, by choice, with the outside of the fabric turned in on the roll. For this purpose the machine is adjustable and convertible from one type of winding to the other.

The operation of adjusting the machine for either kind of winding is very simple and it requires but a moment's time to convert it from one kind of winding to the other.

Another object of the invention is to provide very efficient means for rapidly winding the slit fabric smoothly into even rolls and without injury to the fabric, even though it be of a delicate nature such as knitted rayon.

Another object of the invention is to provide simple means for exerting different pressures upon the fabric which is being wound, in order to wind the fabric as tightly or loosely as desired and according to the nature of the fabric. The present machine may be quickly adjusted to regulate the pressure on the fabric and the adjustment may be made either while the machine is at rest or while it is in operation.

Another object of the invention is to provide a machine in which the rollers may be very easily

and rapidly inserted in and removed from the machine.

Another object is to provide means for exerting pressure upon the fabric as it is wound and without increasing friction or causing binding in the bearings of the winding mandrels.

Other objects and advantages will be set forth in the following detailed description of my invention.

In the drawings forming part of this application,

Figure 1 is an end elevation of a machine embodying my invention in the preferred form,

Figure 2 is a front elevation thereof,

Figure 3 is a sectional view taken on the line 15 3—3 of Figure 2,

Figure 4 is a sectional view taken on the line 4—4 of Figure 2,

Figure 5 is a sectional view showing one of the weighted devices for placing the winding fabric 20 under pressure,

Figure 6 is a similar view but with the parts in position after a considerable quantity of fabric has been wound on a mandrel.

Figure 7 is a sectional view taken on the line 25 7—7 of Figure 6,

Figure 8 is a perspective view corresponding to a sectional view on the line 8—8 of Figure 5,

Figure 9 is a sectional view taken on the line 30 9—9 of Figure 2, showing the machine as set up for winding the fabric with the outside surface turned inwardly of the wound rolls,

Figure 10 is a similar view but with the machine set for winding the fabric with the outside surface turned outwardly of the rolls, and

Figure 11 is a sectional view showing part of the pressure creating devices and one of the winding rollers or mandrels.

In the drawings I have shown a machine mounted on a frame consisting principally of the two end standards 1, 2 with a longitudinal connecting member 3. Adjacent one end of the machine there is shown a motor 4 as a source of power, although it will be understood that any other source of power may be employed for operating the machine. The shaft of the motor is provided with a pulley 5 which operates the belt 6 and the latter in turn revolves the pulley 7 and with it the main shaft 8 from which the power is distributed to the various moving parts of the 50 machine.

There is a small gear 9 on this latter shaft which drives a larger gear 10 carried upon a shaft 11. On the same shaft 11 there is fixed a sprocket wheel 12 which drives an endless chain 13. The 55

latter also engages around the sprocket wheel 14 which is mounted on the shaft 15. The latter shaft has mounted upon it a small gear 16 which meshes with and drives another small intermediate pinion 17. The latter is mounted on a stud or shaft on the arm 18 which is pivoted on the shaft 15 so that the pinion 17 may be moved or caused to turn about the axis of the shaft 15.

The small pinion 17 is adapted to mesh with either of the two gears 19, 20 which are mounted respectively on the shafts 21, 22 which are mounted in parallel relation lengthwise of the machine. The two gears 19, 20 on the shafts 21, 22 also mesh with each other so that these two shafts will be revolved in unison no matter which of the gears 19, 20 the small pinion 17 meshes with. If the pinion 17 meshes with the large gear 19 the large gears 19, 20 and their shafts will be operated in the directions indicated by the arrows in Figures 1; whereas, if the arm 18 is swung over so that the pinion 17 meshes with the large gear 20 then the two gears 19, 20 and their shafts will be revolved in the opposite directions to that shown in Figure 1.

The arm 18 which carries the small pinion is attached to or is part of a lever arm 23 which extends from the left of the axis of the shaft 15 in Figure 1 and on its outer, free end it is provided with a handle 24 adapted to be grasped by the operator for the purpose of rocking the lever arm 18 to bring the small pinion 17 into mesh with either of the two gears 19, 20. I have shown the lever arm 23 provided with an enlargement in which an arcuate slot 25 is formed and through which projects a locking bolt 26 attached to the frame of the machine and which is adapted to be tightened for the purpose of locking the pinion carrying lever in either of its two positions. The two shafts 21, 22 carry the rollers 27, 28 which are adapted to guide and smooth the fabric and to co-operate with the winding mandrels during the winding of the fabric.

I have shown two devices for cutting or slitting the fabric, one being arranged at each side of the flattened tube of fabric and both devices are alike except for the means for adjusting them. Each slitting device consists of a disc or wheel 29 mounted to revolve on the bracket 30 in such position as to engage the outer surface of one edge of the flattened tubular fabric 31.

This wheel has a smooth flat periphery 32, preferably of hardened steel, against which the cutting member is adapted to act in slitting or cutting the fabric. Preferably, these wheels have fixed positions during operation of the machine. The cutting members in the form of revolvable wheels or discs 33 having sharp cutting edges and preferably made of very hard steel, are revolvably carried upon pivotal supports 34 which have portions 35 extending forwardly to guide the fabric and prevent it from getting onto the wrong side of the cutting wheel.

The members 34 which carry the cutting discs are pivotally supported at 36 upon brackets 37 so that they may swing under the action of a coiled spring 38 mounted between a bracket 39 and the free end of the lever arm 40 so that the cutting disc is resiliently pressed with its cutting edge against the face of the opposing wheel 29.

It will be apparent that the cutting disc is located inside the flattened tube of fabric or in other words, between the upper and lower layers 41, 42 of the fabric, whereas the opposing wheel 29 is disposed outside the fabric. This relation-

ship of cutting disc and opposing roller may be reversed but I prefer to have them in the relation above described and as shown in the drawings.

It will be apparent from what has been said that the spring 38 exerts a continuous pressure on the lever arm 40 and that this causes the arm 34 to swing in the direction necessary to press the edge of the cutting disc against the face of the opposing wheel. As has been stated above, there is a cutting device, preferably at each side of the machine, and the lateral distance between them corresponds with the width of the flattened tube of fabric. Each cutting device is mounted on a frame 43 and these frames are slidable along the beam 3 of the machine.

At the right hand end of Figure 2 I have shown a hand wheel 44 mounted on the shaft 45; and this shaft extends through bearing members 46 in the two sliding frames 43 and also through a bearing 47 on the beam 3. The shaft 45 is provided with right and left hand threads 48 respectively corresponding with right and left threads within the bearing members 46.

It will be apparent that if the hand wheel 44 is turned in one direction the sliding frames 43 will both move towards each other like distances, and that if the wheel is turned in the opposite direction the sliding frames 43 will both move away from each other, and due to the reverse threads on the shaft 45 both sliding frames will each move the same distance toward or from the central line of the machine. As the cutting devices are mounted on these sliding frames, the operation of the shaft 45 causes the cutting devices to be moved toward or from each other to position them according to the particular width of the flattened tube of fabric which is to be cut and to be wound on the machine. This is preferable to making adjustment at only one side of the machine as it keeps the fabric central of the various rollers regardless of its width.

The tubular fabric, in flattened condition, is supplied in the form of a roll 50 mounted on an arbor 49 at the lower portion of the machine, with the arbor resting at opposite ends upon idler rollers 51 which support the arbor and the roll of fabric and permit them to revolve easily. The flattened tubular fabric passes from the outer coil of this roll over a guiding bar 52 mounted at the front of the machine upon supporting arms 53 and from there the tubular fabric is threaded over the guide arms 35, thence between the cutting and opposing rollers and into other rollers of the machine, as will be hereinafter set forth.

As will be seen in Figures 9 and 10, there is a bar or rod 55 running lengthwise of the machine and lying adjacent and parallel to the roller 27. There is a similar bar 56 lying adjacent to and parallel with the roller 28. These two bars are used as guides to direct the slit strips of fabric in relation to the respective rollers 27, 28 although in some instances the bar 56 is not used as will appear hereinafter. There is a third bar 57 extending lengthwise of the machine and lying preferably below the roller 27 and spaced from it. This bar is made to be removed. For this purpose one end of the bar is adapted to slide in an aperture in the left hand frame standard 1 in Figure 2, whereas the right hand end is adapted to be aligned with the fixed stud 58 mounted in the right hand standard of Figure 2; and there is a sliding sleeve 59 adapted to fit over the end of the bar 57 and the stud 58.

to hold these two members aligned and to support one end of the bar 57 upon one end of the stud 58, as shown in Figure 2. A set screw 60 is adapted to secure the sleeve to the end of the bar 57 to hold the sleeve in position while the machine is in operation.

To remove the bar 57 it is only necessary to loosen the thumb screw 60 and slide the sleeve to the right in Figure 2 upon the stud 58 until it disengages from the right hand end of the bar 57, whereupon the latter may be moved to the right to detach it from the socket in the left hand standard, whereupon the rod may be removed from the machine.

15 The several bars 55, 56 and 57 are used to guide the fabric and to prevent the edges from curling before the fabric reaches the pressing rollers.

I have shown brackets or supports 61 mounted in diagonal positions, as shown in Figures 1, 5 20 and 6, upon the frame of the machine. These brackets are provided with guiding slots 62 and as the brackets are duplicated at both ends of the machine as shown in Figure 2, the slots at one end of the machine face toward those at the 25 opposite end of the machine.

The guiding wall at one side of each of the slots 62 is provided with a cross opening or slot 63 to receive the ends of the rollers or mandrels to permit them to be moved into the grooves 62 30 whereupon these mandrels or rollers may be moved down in these grooves until they come to rest against the rollers 27, 28 respectively. The rollers or mandrels 64, 65 have caps 66 mounted on each end with ball bearings 67 therein so 35 that the mandrel may revolve very easily within the caps when the latter are engaged by the pressing members.

It is to be understood that there are two angularly disposed brackets 61 at each end of the 40 machine, and the two pairs are preferably inclined in opposite directions, as shown in Figure 1. Except for position, these several brackets are preferably all constructed alike, so that a description of one applies to all of them. In 45 the guiding slot 62 of each guiding bracket there is a sliding member 68 adapted to slide lengthwise of the slot 62 and the lower end of the sliding member is adapted to engage and press down on the cap 66 on the end of one of the 50 mandrels and as there are two of these sliding members at opposite ends of the mandrel, it will be apparent that these sliding members press downwardly on both ends of the mandrel for the purpose of pressing it towards the roller 27 or 55 the roller 28, as the case may be.

There is a bracket 69 projecting laterally from each of the brackets 61 and there is a lever arm 70 pivotally mounted at 71 on this bracket. On the outer free end of this lever arm there is 60 mounted a weight 72 which is adjustable along the lever arm and it is held in various adjusted positions by a set screw 73. This lever arm is provided with an elongated slot 74 through which projects a bolt 75 which is screwed into the sliding member 68 so that the downward pressure of the weight on the lever arm 70 exerts a downward pressure on the slide 68, the bolt 75 travelling in the elongated slot 74 during the swinging of the lever arm 70.

70 There is an ear 76 projecting from the bracket 61 and to this is pivotally attached at 77 an angle lever, one arm 78 of which is pivotally connected with a curved link 79, the other end of the link being connected by a screw 80 to the 75 slide 68. The other arm 81 of this lever is pro-

vided with a handle adapted to be gripped by the operator for the purpose of operating the link 79 and through it raising or lowering the slide 68. When this lever is in the position shown in Figure 5, the lever arm 70 which carries the 5 weight is in its upper position and the slide 68 is also in its upper position; and the parts are self-locking in this position because a line passing through the centers of the screws 80, 82 is slightly below the center of the screw 77, and the 10 action of the weighted arm cannot swing the lever 78, 81 as the latter must be moved to throw the screw 82 past the center of the screw 77 before the slide can lower and move downwardly, so that the parts in this position are self-retaining.

It will be noted in Figure 11 that when the slide 68 is in its lowermost position the bottom end of the slide does not touch the cap 66 on the end of the mandrel so that if the slide is allowed to fall rapidly under the action of the weight the bottom end of this slide will stop just above the cap 66 and this will prevent injury to the mandrel and cap if at this time there is no fabric between the mandrel and the roller 27 or the 20 roller 28 as the case may be.

If the fabric has been built up on the mandrel and between it and the roller 27 or 28, the bottom end of the slide will touch the cap 66 but the fabric between the mandrel and the roller will 30 cushion the blow and prevent injury to the mandrel. The downward movement of the slide is limited to that shown in Figure 11 by engagement of the screw 75 with the bottom edge of the slot 83.

I have mounted a scale 84 in suitable brackets 85 in the front of the machine which scale is provided with markings indicating in inches the width of the flattened tubular fabric which is to be cut on the machine. The pointer 86 carried by 40 one of the carriages 43 co-operates with this scale to indicate the width or distance between the cutting members 33 which is the width of the flattened tubular fabric. As the two sliding frames 43 are moved toward or from each other 45 by the operation of the hand wheel 44 the pointer 86 indicates on the scale the various adjustments, so that the operator may determine the correct setting for the cutting members in relation to the particular width of fabric which is 50 to be slit or cut.

Operation

Preparatory to placing the machine in condition for operation, all of the handles 81 are moved 55 into the lower position shown in Figure 5, there being four such handles arranged two at each end of the machine. This causes all of the sliding members 68 to remain in their upper positions so that the lower ends are above the cross slots 63 permitting the insertion of the mandrels.

Let it be assumed that in the operation now being described the strips of fabric are being so wound upon the mandrels that the surfaces of 60 the strips which are the outer side of the fabric before the slitting operation takes place, will be turned inside of the rolls of fabric which are wound upon the mandrels. This setting of the machine is indicated in Figure 9, in which case 70 the bar 57 is present in the machine and it is held at one end by the sleeve 59 which also engages the stud 58 and with the opposite end of the bar fitted into a bearing aperture in one of the end standards.

The tubular fabric is first threaded over the bar 52 and then over the guide plates 94 at opposite sides of the machine in the form of a flattened tube and the fabric is also threaded over 5 the arms 34 and thence between the cutting members and the opposing discs. It will be understood that prior to this operation the wheel 44 will have been turned to adjust the distance between the two cutting devices at opposite sides 10 of the machine to correspond with the width of the flattened tubular fabric.

The leading end of the fabric having been fed between the cutting and opposing rollers, the cutting rollers at opposite sides of the machine being 15 gin to cut the fabric so that two independent strips 87, 88 are formed. One of these strips (87) is threaded by hand under the guide bar 55, thence partly over the pressing roller 27 and the free end of this strip is either attached to the 20 mandrel 64 or one or more turns of the fabric on the latter are made, so that the mandrel will thereafter be able to draw on this strip of the fabric. The end of the lower strip (88) of fabric is carried by hand under the guide bar 51, thence 25 forwardly and under the guide bar 56 and thence partly around the left side of the pressing roller 28 in Figure 9 and the free end of this strip is either attached to the mandrel 65 or several turns are made on the mandrel so that the latter 30 may draw the strip of fabric in the subsequent operations.

It will be noted that the strip 87 is started clockwise around the mandrel 64 while the strip 88 is started counter-clockwise around the mandrel 65 as indicated in Figure 9. It will be observed that the two pressing rollers 27 and 28 revolve in opposite directions. Prior to threading the strips into the machine in the manner described, it is necessary to insert the mandrels.

40 Each mandrel is moved into position so that its cap 66 at each end may be inserted through the side slot 63 of the brackets 61 and then the mandrels are either dropped or moved downwardly so that the caps 66 travel downwardly in 45 the slots 62 until the mandrels come to rest against the rollers 27 and 28 respectively. Both mandrels are inserted into position in the same manner. At this time the slides 68 are in their raised positions as shown in Figure 5.

50 When the mandrels have been thus placed in operative position and the leading ends of the two strips of fabric have been attached to or started on the mandrels, all of the various handles 81 will be swung upwardly by the operator 55 into the positions shown in Figure 6. This operation will cause the lever arm 78 of each device to act through the link 79 and to move the slide 68 downwardly in the slot 62. The lower end of the slide 68 will then come to rest as shown in Figure 11 just out of contact with one of the caps 66 on the end of the mandrel. The machine is now ready for operation.

The belt 6 will be shipped to the fast pulley 7 65 and this will start the various parts of the machine into operation. The pinion 17 with the machine in the condition as shown in Figure 9 and as now being described, will be in mesh with the gear 19 as shown in Figure 1, the lever arm 70 23 being held in position to effect this condition by the bolt 26. Power will be transmitted from the shaft 8 through the small gear 9 which meshes with the larger gear 10 and this will operate the shaft 11. On the shaft there are two bevel gears 75 90 which mesh with bevel gears 91 mounted on

the lower ends of the vertical shafts 92. The opposing rollers 29 are mounted on the upper ends of the shafts 92 so that these rollers are operated anti-clockwise as viewed in Figure 3 so that the fabric will pass the slitting device with the least 5 resistance.

As the cutters 33 are held in contact with the peripheries of the opposing rollers the cutting members will be revolved by contact with the opposing rollers, clockwise as viewed in Figure 10 3, and therefore the cutting and opposing rollers at the bight of these two rollers will be travelling in the same direction as the fabric.

Power is transmitted from the shaft 11 through the sprocket 12 and the chain 13 to the sprocket 15 wheel 14 on the shaft 15. From there the power is transmitted to the intermediate pinion 17 to the gear wheel 19 which is on the shaft of the pressing roller 27. As the gear 19 is in mesh with the gear 20 on the shaft of the other pressing roller, both pressing rollers will be revolved but in opposite directions as indicated in Figure 9. As the fabric is cut or slit at both sides by the cutting members, the two strips 87, 88 are formed from the tubular fabric and they are wound up on the separate mandrels.

The revolving of the pressing roller 27 causes the mandrel 64 to be revolved in a clockwise direction in Figure 9, so that the strip 87 is wound upon this mandrel. As soon as the strip of fabric has made a few turns on the mandrel the caps 66 on the ends of this mandrel will rise into contact with the lower ends of one pair of slides 68 and thereafter the downward pressure of the weights 72 acting on the slides 68 will exert downward pressure on both ends of the mandrel to keep the strip of fabric which is wound upon this mandrel tightly against the pressing roller 27. The strip 87 is therefore smoothed out on the pressing roller 28 as it winds up on the mandrel 64. The tension under which the strip of fabric is wound on the mandrel will depend upon the downward pressure on the slides 68 exerted by the weights 72 and this pressure may be regulated by adjusting the weights toward or from the axis of the lever arms 70 which carry the weights.

It may be desirable to wind different fabrics under different tensions and this may be done 50 by adjusting the positions of the weights as described.

It will be observed that the caps 66 which are in contact with the lower ends of the slides 68 do not revolve in relation to the slides, so that 55 there is no friction between the slides and these caps. The mandrel will turn easily within the caps because of the ball bearings 67. There will be substantially no frictional resistance to the turning of the mandrel due to the pressure of the 60 slides.

The strip 88 passes under the bar 51 and under the bar 56, thence partly around the pressing roller 28 and it winds on the mandrel 65 in a counter clockwise direction as viewed in Figure 65 9. When several turns of the fabric have been wound upon the mandrel 65 the latter will have risen until its caps 66 engage the lower ends of the corresponding slides 68 and from then on the slides exert a downward pressure on the mandrel 65 the same as on the mandrel 64. In other words, both mandrels perform the same function and in the same way except that they revolve in opposite directions.

It will be noted that the surface of the strip 75

87 which was part of the outer surface of the fabric while it was in tubular form will be turned to the inside as the roll of fabric is built upon the mandrel 64. It will also be noted that the 5 under side of the strip 88 which was part of the outer surface of the tubular fabric before it was slit, is also turned inwardly as the roll of fabric is built up on the mandrel 65. In other words, both strips are wound on the mandrels with the 10 exterior surfaces of the strips turned inwardly.

When the machine is in the condition shown in Figure 9, therefore, both strips of fabric will be wound on their respective mandrels with the outer surface of the fabric turned inwardly; or, 15 in other words, all rolls of fabric slit and wound on the machine will be in the same condition.

It will be noted that the two strips engage with approximately the same extent of the respective 20 pressing rollers. If it is desired to wind the strips of fabric so that the surfaces which were the outer surfaces before the tube is split, turn outwardly on the wound rolls, then the machine will be placed in the condition shown in Figure 10. To do this several operations are necessary. One 25 of these is to swing the lever arm 23 downwardly in Figure 1, first slackening off the bolt 26. When this lever arm is swung downwardly the arm 18 will carry the pinion 17 out of mesh from the gear 19 and throw it into mesh with the gear 30 20. This will cause the pressing rollers 27 and 28 to revolve in the reverse directions to what they did in Figure 9. The bar 51 will be removed from the machine in the manner described above. The fabric will be threaded through the cutting 35 devices in the same manner as described above but this time the severed strip 87 of the fabric will pass over the bar 35 and under the bar 55 and thence partly around the pressing roller 27 in a clockwise direction in Figure 10. The end of this strip of fabric will be attached to the mandrel 64 but instead of the strip of fabric winding onto this mandrel in the manner shown in Figure 9, it will wind in the opposite direction because the pressing roller 27 revolves in the 40 opposite direction to that which it did in Figure 9. 45

The strip 88 will pass under the arm 35 and it will then press against the strip 87 and a portion of the pressing roller 27 and from there the strip will pass onto the surface of the pressing roller 28 in a counter clockwise direction, and the free end will be attached to the mandrel 65. In this instance, however, the mandrel 65 will 50 revolve clockwise. It will now be apparent that as the pinion 17 is in mesh with the gear 20 instead of with the gear 19, both pressing rollers and both mandrels will be revolved in directions 55 reverse to those shown in Figure 9.

It will be apparent that the upper surface of the strip 87 will be wound outwardly on the mandrel 64 and the bottom surface of the strip 88 will be wound on the outside on the mandrel 65. These respective surfaces were the outer surface of the tubular fabric in advance of the cutting operation.

65 From this it will be observed that both severed strips are wound alike on the mandrels with the outer surface of the fabric disposed outwardly on the two mandrels. From what has been described it will be apparent that the machine may be set 70 to wind up both strips alike and to have the outer surface of the fabric disposed on the outside of the rolls or turned inwardly of the rolls. Heretofore this result could not be obtained with any machine as far as I am aware.

When the fabric is built up on the mandrels 64 and 65 to the desired maximum size, the mandrels will have been lifted so that the caps 66 are in line or register with the side slots 63, so that the operator merely has to move the mandrels and 5 rolls of fabric sidewise through the slots 63, whereupon the mandrels and the fabrics may be removed from the machine. This method of removing the rolls of fabric is simple and it is less 10 harmful to the operator.

With the parts arranged as shown in Figures 9 or 10 the fabric strips from the time they are severed from the tube until they are wound on the mandrel, are guided in such manner that the fabric cannot curl at the edges and because of 15 this I am enabled to wind the fabric smoothly on the mandrels from edge to edge. Heretofore the edges of the fabric have curled or folded in so that it was necessary to trim off from each 20 roll of fabric wound on the mandrel the turned in or curled portion, and this caused considerable waste of material. Where the fabric is slit and wound on the present machine there is no such loss as it is not necessary to trim off the end of the rolled fabric.

25 As far as I know this is the first machine in which it has been possible to wind both severed strips upon the mandrels with the outer surfaces of the severed strips turned inwardly or outwardly on the two rolls of fabric. Heretofore 30 it has been necessary to wind one roll with the outer surface turned inwardly and with the outer surface turned outwardly of the other roll.

Having described my invention, what I claim is:

1. In a machine of the class described, means 35 for guiding a tubular fabric in the form of a flattened tube, devices for simultaneously cutting the tubular fabric at opposite sides thereof, movable carriers on which said cutting devices are 40 mounted, and means for simultaneously moving said carriers toward and from each other in opposite directions.

2. In a machine of the class described, means 45 for guiding a tubular fabric in the form of a flattened tube, devices for simultaneously cutting the tubular fabric at opposite sides thereof, movable carriers on which said cutting devices are mounted, means for simultaneously moving said carriers toward and from each other in opposite 50 directions, including a shaft having right and left threads engaging said carrying devices, respectively, for effecting the movement of said carriers.

3. In a machine of the class described, means 55 for guiding a tubular fabric in the form of a flattened tube, and means for cutting the tubular fabric simultaneously at opposite sides to divide the same into a plurality of strips, including cutting discs disposed inside the tubular fabric, 60 and flat faced opposing rollers disposed outside the tubular fabric at each side thereof and co-operating with said cutting disc to simultaneously cut the fabric at opposite sides thereof.

4. In a machine of the class described, means 65 for feeding a tubular fabric in flattened form, means for cutting the fabric at opposite sides to form separate strips, rollers around which the separate strips are individually guided, and means for separately rolling up the strips of 70 fabric into separate rolls.

5. In a machine of the class described, means 75 for feeding a tubular fabric in flattened form, means for cutting the fabric at opposite sides to form separate strips, rollers around portions of

which the separate strips are individually guided in relatively opposite directions, and means for separately rolling up the strips of fabric into separate rolls.

5 6. In a machine of the class described, means for feeding a tubular fabric in flattened form, means for cutting the tubular fabric at opposite sides to form separate strips, rollers around portions of which the separate strips are individually guided in relatively opposite directions, means for separately rolling up the strips of fabric into separate rolls, and means for revolving said rollers in relatively opposite directions.

10 7. In a machine of the class described, means for feeding a tubular fabric in flattened form, means for cutting the tubular fabric at opposite sides to form separate strips, a roller partially around which one of said strips engages with the surface which was the inner surface of the strip before being severed from the tube, means for winding said strip into a roll with said inner surface directed outwardly of the roll, a second roller around which the second strip of fabric partially travels with its inner surface in contact with said roller, and means for winding said second strip into a roll with the inner surface of the fabric facing outwardly of said latter roll.

15 8. In a machine of the class described, means for feeding a tubular fabric in flattened form, means for cutting the tubular fabric at opposite sides to form separate strips, a pair of rollers around portions of which the separate strips individually engage, means for revolving said rollers in opposite directions, and means for winding up said strips individually in rolls.

20 9. In a machine of the class described, means for feeding a tubular fabric in flattened form, means for cutting the tubular fabric at opposite sides to form separate strips, a pair of rollers, one of the severed strips engaging partly around one of said rollers, the other strip engaging around a portion of the other of said rollers, means for revolving said rollers in opposite directions, arbors on which the strips of fabric are adapted to be individually wound, said arbors with the fabric thereon adapted to rest against said rollers whereby the arbors and their fabric are revolved by said rollers.

25 10. In a machine of the class described, means for feeding a tubular fabric in flattened form, means for cutting the tubular fabric at opposite sides to form separate strips, a pair of rollers and means for operating them in opposite directions, guide bars for guiding the individual strips separated from the tubular fabric whereby the strips engage respectively around portions of said rollers in opposite directions, and means for separately rolling up the strips after engagement with said rollers.

30 11. In a machine of the class described, means for feeding a tubular fabric in flattened form, means for cutting the tubular fabric at opposite sides to form separate strips, a pair of rollers around portions of which the separate strips are adapted to respectively engage, arbors on which the strips are wound and so mounted that the fabric on the arbors rests against the respective rollers whereby the arbors are revolved by the rollers, and means for revolving said rollers in relatively opposite directions and for reversing the directions of said rollers.

35 12. In a machine of the class described, means for feeding a tubular fabric in flattened form, means for cutting the tubular fabric at opposite sides to form separate strips, a pair of rollers

around portions of which the separate strips are adapted to respectively engage in opposite directions, means for winding up the separate strips, meshing gears associated with said rollers and a pinion adapted to be meshed with either of the gears of said rollers whereby said rollers may be operated in unison and reversed in direction.

40 13. In a machine of the class described, means for feeding a tubular fabric in flattened form, means for cutting the tubular fabric at opposite sides to form separate strips, a pair of rollers around portions of which the separate strips are adapted to respectively engage, guiding means associated with said rollers and so related thereto that said strips may be directed to travel clockwise or anticlockwise around said rollers, and means for separately winding up the separate strips in separate rolls.

45 14. In a machine of the class described, means for feeding a tubular fabric in flattened form, means for cutting the tubular fabric at opposite sides to form separate strips, a roller, a guide member for guiding one of the strips of fabric onto said roller in an anticlockwise direction and adapted to permit said strip to be threaded so as to travel clockwise around said roller, an arbor for winding up said first strip of fabric and engaging said roller whereby the arbor may be revolved in either direction, a second roller, a guiding member for directing the second strip of fabric clockwise onto said second roller and adapted to permit said second strip to be threaded so as to travel anticlockwise on said roller, an arbor for winding said second strip and adapted to be revolved by said second roller in either direction, and means for revolving said rollers in relatively opposite directions and for reversing the directions of said rollers.

50 15. A machine of the character described, including a roller around a portion of which a strip of fabric is adapted to travel, an arbor on which the strip of fabric is adapted to be wound and to be propelled by said roller, guides for guiding the ends of the arbor to move toward and from said roller, sleeves on the ends of said arbor in which the arbors are adapted to revolve, and means for applying pressure to said sleeves to hold said arbor with the fabric wound thereon against said roller.

55 16. A machine of the character described, including a roller around a portion of which a strip of fabric is adapted to travel, an arbor on which the strip of fabric is adapted to be wound and to be propelled by said roller, guides for guiding the arbor to move toward and from said roller, means for applying pressure to hold said arbor with the fabric wound thereon against said roller, and means for limiting the movement of said pressure means so that the arbor is not put under pressure until a portion of the strip of fabric has been wound thereon.

60 17. A machine of the character described, including a roller around a portion of which a strip of fabric is adapted to travel, an arbor on which the strip of fabric is adapted to be wound and to be propelled by said roller, guides for said arbor to permit the arbor to move toward and from said roller, said guides having tracks in which the ends of the arbor may move, sliders in said tracks adapted to apply pressure to the arbor to move it towards said roller, said guides having an opening for the lateral passage of the arbor to disengage it from said tracks, said lateral openings being so positioned that when a

roll of fabric has been built upon said arbor the latter will be adjacent said openings.

18. A machine of the character described, including a roller around a portion of which a strip of fabric is adapted to travel, an arbor on which the strip of fabric is adapted to be wound and to be propelled by said roller, guides for guiding said arbor to move towards and from said roller, sleeves on the ends of said arbor and in which sleeves the arbor is adapted to revolve, ball bearings interposed between said sleeves and said arbor, and means for applying pressure to said sleeves to hold said arbor with the fabric wound thereon against said roller.

19. A machine of the character described, including a roller around a portion of which a strip of fabric is adapted to travel, an arbor on which the strip of fabric is adapted to be wound and to be propelled by said roller, guides for guiding the arbor to move toward and from said roller, sliding means for applying pressure to hold said arbor with the fabric wound thereon against said roller, and weighted levers for pressing said sliding means.

20. A machine of the character described, including a roller around a portion of which a strip of fabric is adapted to travel, an arbor on which the strip of fabric is adapted to be wound and to be propelled by said roller, guide members having tracks for guiding the ends of the arbor to permit the arbor to move toward and from said roller, slides moving in said tracks and adapted to apply pressure to said arbor, and weighted levers for moving said slides to apply pressure to said arbor.

21. A machine of the character described, including a roller around a portion of which a strip of fabric is adapted to travel, an arbor on which the strip of fabric is adapted to be wound and to be propelled by said roller, guide members having tracks for guiding the ends of the arbor

to permit the arbor to move toward and from said roller, slides moving in said tracks and adapted to apply pressure to said arbor, weighted levers for moving said slides to apply pressure to said arbor, and releasable means for locking said weighted levers in raised, inoperative position.

22. A machine of the character described, including a roller around a portion of which a strip of fabric is adapted to travel, an arbor on which the strip of fabric is adapted to be wound and to be propelled by said roller, tracks for guiding said arbor to move toward and from said roller, slides guided by said tracks for applying pressure to said arbor, weighted levers connected with said slides to operate the same to apply pressure to said arbor, hand operated levers, links connected between said latter levers and said slides in such manner that said weighted levers will be locked in raised, inoperative position by said links, subject to release by said hand operated levers.

23. A machine including a roller around a portion of which a strip of fabric is adapted to travel, an arbor on which the strip of fabric is adapted to be wound and to be propelled by said roller, inclined guiding members having tracks in which the ends of the arbor are guided to permit the arbor to move toward and from said roller, slides movable in said tracks and adapted to press said arbor towards said roller, levers having adjustable weights thereon, said levers pivotally supported by said guiding members and pivotally connected with said slides to exert downward pressure thereon, hand levers pivotally supported by said guides, links pivotally connected with said latter levers and said slides and operating to lock said weighted levers out of operation in raised position, subject to release by said hand levers.

OSCAR I. JUDELSHON. 40
